UNITED STATES PATENT OFFICE.

PERRY J. SWEENEY, OF WHITING, INDIANA, ASSIGNEE TO STANDARD OIL COMPANY, OF WHITING, INDIANA, AND CHICAGO, ILLINOIS, A CORPORATION OF INDIANA.

CONVERSION OF HIGH-BOILING HYDROCARBON OILS INTO LOWER-BOILING OILS.

Application filed January 11, 1926. Serial No. 30,565.

The present invention relates to improvements in the conversion of hydrocarbon oils of higher boiling points than gasoline into hydrocarbon oils of the gasoline range of 5 boiling points. It will be fully understood from the following description, illustrated by the accompanying drawing, in which apparatus for carrying the invention into effect is diagrammatically illustrated, partially in elevation.

Referring more particularly to the drawings, the numeral 5 indicates a suitable furnace setting in which is mounted a heating coil 6, to which oil to be operated upon 15 is supplied through the inlet line 7. The heated oil passes from the coil 6 through the line 8 into a manifold 9. From the manifold 9 valved feed lines 10, 11, 12 and 13 lead to the chambers 14, 15, 16 and 17 respectively. 20 Each of the chambers 14, 15, 16 and 17 is provided with a valve draw-off line, these being numbered 18, 19, 20 and 21. These draw-off lines lead to a common tar manifold 22, which leads, for example, to a tar 25 heat exchanger and storage receptacle (not shown) or other suitable devices. The chambers 14, 15, 16 and 17 are interconnected at approximately the level of liquid maintained therein by the pipes 24; and 30 their vapor spaces are interconnected by the pipes 25. A vapor line 26 leads from the vapor space of one of the interconnected chambers, for example, 17, to the lower portion of a dephlegmating tower 27. Vapors 35 heavier than the desired distillate product are condensed within the dephlegmator 27, the cooling action being aided by a suitable reflux cooling coil provided in the upper portion of the dephlegmator 27, the 40 cooling medium being supplied thereto through the pipe 28 and, leaving the dephlegmator, somewhat preheated, through the line 29. Uncondensed vapors pass out of the dephlegmator 27 through the line 30 to a suitable condenser 31, the condensate being collected and separated from accompanying gas in the receptacle 32.

Inasmuch as oil of a character suitable 50 to be charged in the system is preferably used as the cooling medium in the upper portion of the dephlegmator, the line 29 is suitably extended to communicate with the inlet line 7 of the heating coil 6. Reflux condensate from the dephlegmator 27 is 55 likewise preferably withdrawn by a line 33

and forced by a pump 34 through line 35 to the inlet 7 of the heating coil 6.

The oil to be treated in accordance with this invention is supplied through the inlet 7 to the heating coil 6 in which it is brought 60 to a conversion temperature above 700° F., and preferably in the neighborhood of 800° F., although temperatures as high as 950 to 1000° F. may be employed. The pressure at the outlet of the coil and throughout 65 the remainder of the system is maintained in excess of 60 pounds gauge and preferably at 200 pounds or higher. The oil is caused to flow through the heating coil at a rate of speed sufficient to prevent any substantial 70 deposition of coke therein.

From the coil 6, the heated oil passes through the line 8 to the manifold 9. The supply of oil from the manifold to the enlarged chambers 14, 15, 16 and 17, and the withdrawal of oil therefrom is so controlled that the oil flows in series through the enlarged chambers at a greatly reduced rate of speed, being maintained therein at conversion temperatures whereby substantial 75 conversion is effected therein. If desired, mild heat may be supplied to the chambers so that no very substantial drop of temperature will take place therein. Thus, the temperature of the oil within the chambers 80 14, 15, 16 and 17 may be 50° less than that at the outlet of the coil 6, or the differential may be even less than this. Thus, with a coil outlet temperature of 800 to 810° F. the oil in the enlarged chambers may well 85 be maintained at 780 to 790° F. The vapors from the intercommunicating vapor spaces of the chambers pass through the line 16 to the dephlegmator, as already fully 90 set forth.

In the initial stages of operation, the oil may be passed, for example, from manifold 9 through line 10 into still 14, or through lines 10 and 11 into chambers 14 and 15. Tar may be withdrawn continuously or intermittently from the chamber 17 or from chambers 16 and 17. Thus it has been found satisfactory to withdraw substantially three-fourths of the tar removed from the still 17 through the line 21, the remaining one-fourth 100 being drawn from the chamber 16 through the line 20. After the operation has been conducted in this manner for a period of time sufficient to cause a substantial formation of coke and asphaltic matter in the 105 110

chambers 16 and 17, in accordance with the present invention the direction of flow through the chambers is reversed, the lines 10 and 11 to the chambers 14 and 15 being closed and the heated oil being fed from the manifold 9 through the line 13 into the chamber 17 or through the lines 12 and 13 into the chambers 16 and 17. At the same time, the withdrawal of tar from the chambers 17 and 16 is discontinued, and tar is drawn from the chamber 14 through the line 18 or from the chambers 14 and 15 through the lines 18 and 19, for example, in the same manner as tar was previously withdrawn from the chambers 17 and 16. As a result of the reversal of flow of the oil, it is found that there is a substantial reduction in the coke and asphaltic accumulations in the chambers 17 and 16, which were formerly at the end of the series, and coke and asphaltic accumulations apparently begin to build up in the stills 14 and 15, which are now at the end of the series. When these accumulations become substantial, as indicated by the character and flow of the tar or by other indicia, the direction of flow is again reversed, flow being resumed as originally described. In this manner, the flow is reversed at intervals during the operation of the system, and the length of a run has thereby been substantially increased. Thus, runs up to and exceeding 700 hours in length have been made when operating in accordance with the present invention.

Although the invention has been described in connection with the reversal of flow through the enlarged chambers after appreciable accumulations of coke and asphaltic matter in certain thereof, it is readily apparent that such accumulations may be foreshadowed by an earlier reversal of flow in the manner above set forth, such substantial accumulations of coke and asphaltic matter being thereby prevented. Thus, in the early stages of the run, the direction of flow may be reversed every 36 or 48 hours, the intervals between reversals being shortened at later stages in the run to, say 24 hours.

It is not intended that the details of apparatus illustrated nor of the process as

above set forth shall be regarded as limitations upon the scope of the invention, except in so far as included in the accompanying claims.

I claim:

1. In the method of producing low boiling hydrocarbon oils of the gasoline range of boiling points from higher boiling hydrocarbon oils, passing the higher boiling oil in continuous flow in a restricted stream through a heated zone in which it is brought to conversion temperature, then causing the heated oil to pass at a slower rate in succession through a plurality of enlarged chambers at conversion temperatures, while maintaining pressure upon the oil throughout the system, whereby substantial conversion takes place therein, and at intervals reversing the flow of the oil through said enlarged chambers.

2. The method of producing low boiling point hydrocarbon oils in the gasoline range of boiling point from higher boiling hydrocarbon oils which comprises passing the higher boiling oil in continuous flow in a restricted stream through a heating zone in which it is brought to conversion temperature, discharging the heated oil from said stream into one of a plurality of series connected enlarged chambers through which the oil is caused to flow at a slower rate while conversion temperature is maintained therein, pressure being maintained upon the system, withdrawing liquid products of conversion from another of said enlarged chambers remote from the one into which the oil is caused to flow from the heating zone, continuing the flow of oil through the enlarged chambers until substantial coke and asphaltic depositions take place in the later ones of the series of enlarged chambers, and then changing the flow of oil from the heating zone to a chamber from which liquid products were previously withdrawn and withdrawing liquid products of conversion from a chamber into which oil was previously admitted from the heating zone, thereby reversing the flow of oil through the series of enlarged chambers.

PERRY J. SWEENEY.
